FLOOR MACHINE

Hendrik W. Lundquist, Tujunga, Calif.

Application February 12, 1944, Serial No. 522,075

11 Claims. (Cl. 15—50)

1

My invention relates to a floor machine, for sanding, scrubbing, and polishing floors.

One of the principal objects of this invention is to provide a machine of this class which is compact and relatively silent in its operation.

Another important object of this invention is to provide a floor machine in which the power for operating the sanding, scrubbing, and polishing elements is frictionally connected to these elements for operating the same.

An important object also of this invention is to provide a novel mounting of the power unit for a frictionally driven machine of this class, whereby the power unit is yieldably connected to the driven member in such a manner that there is no undue wear or shock between the frictionally connected operating members.

A feature of this invention is to provide a novel structure for supporting the ultimate drive member and floor-operating implement.

Another novel feature of my invention is to provide a simple and rigid means of mounting the enclosing housing of my machine.

A further object of this invention is to provide a novelly constructed clutch for detachably connecting, sanding, scrubbing, or polishing elements or implements to the supporting and driving member.

A still further object of this invention is to provide such a clutch for connecting either right or left hand driven sanding, scrubbing, and polishing elements or implement.

Still another object of this invention is to provide either a single or a multiple floor-operating-element machine incorporating the aforementioned features.

With these and other objects in view, as will appear hereinafter, I have devised a floor machine having certain novel features of construction, combination, and arrangement of parts and portions, as will be hereinafter described in detail and particularly set forth in the appended claims, reference being had to the drawings, and to the characters of reference thereon, which form a part of this application, in which:

Fig. 1 is a fragmentary sectional elevational view of my floor machine in one form of construction, with the section taken through 1—1 of Fig. 2;

Fig. 2 is another fragmentary sectional elevation thereof taken through 2—2 of Fig. 1;

Fig. 3 is a fragmentary view in plan, showing the motor mounting, taken through 3—3 of Fig. 1;

Fig. 4 is a transverse sectional view, taken

2

through 4—4 of Fig. 2, showing the means of removably securing the sanding, scrubbing and polishing elements or implements to the supporting and rotating member;

5 Fig. 5 is a sectional elevation of a floor machine, in a modified form, incorporating the features of my invention, the section being taken through 5—5 of Fig. 6; and,

Fig. 6 is a fragmentary sectional elevation 10 thereof, taken through 6—6 of Fig. 5.

My machine, as shown in Figs. 1 and 2 is enclosed in a unitary housing 1 which is normally supported by or on the element or floor operating implement driven by the machine, such as 15 the brush 2 shown in Figs. 1 and 2. The machine is moved over the floor by means of a handle 3. At one side of the housing is a wheeled carriage which consists of a frame 4 and wheels 5. The frame 4 is pivotally connected to the 20 housing 1 in such a manner that when the frame is swung downwardly and forwardly, the machine may be transported from place to place on wheels. When the machine is in use and rests on the floor by means of the brush, or one of the other 25 elements or implements, the frame 4 may be swung upwardly so that the wheels 5 are out of the way.

The motor 11 and drive elements 12 and 13 are enclosed within the housing. The motor, 30 which is here shown as an electric motor, is carried on a U-shaped cradle 14, which is supported or suspended by its legs from the opposite side walls of the housing 1 by arms 14^a. Or the structure may be defined such that the housing is supported on the ends of the arms 14^a of the support. As shown, the motor rests directly upon the motor base 15 which is pivotally mounted at one side or end on a pair of lugs 14^b at one end of the cross-portion 14^c of the cradle 14. The axis of the pivot pin 16, which pivotally supports the motor base on the cradle, is parallel to the rotating axis of the motor. The free end of the base, or the end opposite the pivotal mounting, is supported by compression springs 17 located between the base and the opposite end of the cross-portion of the cradle. The base is secured relative to the cradle by means of a bolt 18 and nuts 19. Compression springs 20 are positioned between the base and the nuts so as resiliently to clamp the free end of the base upon the springs 17.

The motor base 15 is also U-shaped, the same being provided with saddle-shaped legs 15^a, which embrace the journals 11^a of the motor. The journals are secured in the saddles by straps

21 which extend over the upper portions of the journals.

The drive member 12 is mounted at one end of the shaft 11^b of the motor. The contour of the drive member 12 is similar to a bevel pinion, while the contour of the corresponding or engaging surface 13^a of the drive member 13 is shaped generally as the surface of a large bevel gear. This drive member 13 is cup shaped, and the lower portion of the cradle, the motor base, and the lower portion of the motor are located therein.

The drive member 13 has a downwardly extending boss 13^b around which fits the hub or backing plate 2^a of the brush or other element 2.

Into this hollow boss 13^b extends a stub shaft 14^d which extends downwardly from the middle of the U-shaped portion of the cradle. The driven member 13 is centered and also carried by this stub shaft. Ball bearings 14^c provide the mounting of the drive member 13, or the hollow boss 13^b of the drive member, about the stub shaft. The ball bearings, and therefore, the driven member 13, are retained on the stub shaft by a plate 14^e secured to the end of the stub shaft.

The brush is secured to the bottom portion of the driven member 13 by a pair of clutch members 22 and 23. Both are substantially similar and both are provided with, preferably three, fingers. It will be noted however that each gripping portion of the clutch 22 is substantially T-shaped, the cross portion 22^a thereof comprising a pair of opposed fingers, so as to receive the laterally extended portion of the finger of the lower clutch member 23. If desired, the lower clutch member may also have T-shaped fingers forming pairs of opposed fingers, so that the brush, or other implement, may be secured to the driven member for rotating the brush, or the like, in opposite directions.

It will be here further noted that the free ends of the fingers, that is, the lateral portions of the L-shaped fingers and the opposite ends of the cross portions of the T-shaped fingers, may be readily depressed, so as to take up wear and thereby cause the brush, or other implement, to be tightly secured to the upper clutch member and to the driven member 13.

In Figs. 5 and 6 of the drawings, the housing 31 is made relatively long and narrow for the purpose of mounting two brushes or other implements 32 and 33. Both of the brushes are provided with drive members 34 and 35 which are rotated in opposite directions by a pair of friction drive members 36, one mounted on each end of the motor 37. In this instance, the motor base 38 is resiliently supported on a plate 39 which is secured over and seals the bottom of the housing 31.

The driven or rotating members 34 and 35 are secured to the upper ends of shafts 40 which are rotatably mounted on vertical axes in journals 39^a which are supported on and extend upwardly from the plate 39. In the journals are ball bearings 41 which carry the shafts 40. The brushes, or other floor implements, are detachably secured from the lower ends of the shafts by the clutch members 22 and 23, secured respectively to the shaft and the implement.

In the double machine, the motor base is preferably pivotally mounted at one end on a single lug 39^a on the plate 39 so that the base may be readily twisted, rocked, or adjusted laterally by two screws at the free end, as shown

in Figs. 3 and 5, for variously adjusting the friction drive members 36, at the opposite ends of the motor, with respect to the driven friction members 34 and 35.

Though I have shown and described a particular construction, combination, and arrangement of parts and portions, and certain modifications thereof, I do not wish to be limited to the same, but desire to include in the scope of my invention the construction, combination, and arrangement substantially as set forth in the appended claims.

I claim:

1. In a machine of the class described, a motor support, a motor mounted thereon, a drive member on the motor, a cup-shaped driven member, the support and motor being located within the driven member, the drive member operatively engaging the rim of the driven member, said motor support having a depending shaft at its middle portion, the driven member being rotatably mounted about said shaft and retained thereby, and a floor implement carried by and depending from said driven member.

2. In a machine of the class described, a motor support, a motor mounted thereon, a drive member on the motor, a driven member operatively connected to the drive member, said motor support having a depending shaft at its middle portion, the driven member being rotatably mounted about said shaft and retained thereby, a floor implement carried by and depending from said driven member, said motor support having laterally extending arms, and a housing supported on said arms enclosing said motor and said driven member and positioned above said floor implement.

3. In a machine of the class described, a U-shaped motor support, a motor supported within the U-shaped portion of the support, a drive member on the motor, a cup-shaped driven member rotatably mounted around the U-shaped portion of the support, the cross-portion of the U-shaped support having a stub shaft extending downwardly from its middle portion, the axial portion of the driven member being rotatably mounted on and retained by said shaft, and a floor implement carried by and depending from the axial portion of said driven member.

4. In a machine of the class described, a U-shaped motor support, a motor supported within the U-shaped portion of the support, a drive member on the motor, a cup-shaped driven member rotatably mounted around the U-shaped portion of the support and supported at its axial portion from the middle and lower portion of the support, a floor implement carried by and depending from the driven member, said U-shaped support having arms extending laterally from the upper ends of its legs, and a housing supported on the outer ends of the arms.

5. In a machine of the class described, a motor support, a motor mounted thereon, a friction drive member on the motor, a cup-shaped driven member, the support and motor being located within the driven member, the drive member frictionally engaging the rim of the drive member for rotating the same, said motor support having a depending shaft at its middle portion, the driven member being rotatably mounted about said shaft and retained thereby, and a floor implement carried by and depending from said driven member.

6. In a machine of the class described, a motor support, a motor resiliently mounted thereon, a friction drive member on the motor, a friction

driven member operatively and yieldingly connected to the drive member, said motor support having a depending shaft at its middle portion, the driven member being rotatably mounted about said shaft and retained thereby, and a floor implement carried by and depending from said driven member.

7. In a machine of the class described, a U-shaped motor support, a motor supported within the U-shaped portion of the support, a friction drive member on the motor, a cup-shaped friction driven member rotatably mounted around the U-shaped portion of the support and supported from the support, the cup-shaped driven member having a friction surface at its brim operatively connected to said friction member, and a floor implement carried by and depending from the driven member.

8. In a machine of the class described, a U-shaped motor support, a motor resiliently supported within the U-shaped portion of the support, a friction drive member on the motor, a cup-shaped friction driven member rotatably mounted around the U-shaped portion of the support and supported at its axial portion from the middle and lower portion of the support, the cup-shaped driven member having a friction surface at its brim operatively and yieldingly connected to said friction member, and a floor implement carried by and depending from the driven member.

9. In a machine of the class described, a U-shaped cradle, a motor resiliently mounted in the depression of the cradle, a bevelled friction drive member on the shaft of the motor, a cup-shaped friction driven member positioned around the cradle and provided at its brim with a bevelled friction surface, the friction member being resiliently urged in operative engagement with said surface, the middle portion of the cradle having a depending shaft, the axial portion of the driven member being rotatably supported on and by said shaft, and a floor implement secured to said driven member.

10. In a machine of the class described, a U-shaped cradle, a motor positioned in the depression of the cradle and provided with a base, one

5 end of said base being pivotally supported within the depression of the cradle, the opposite end of the base being resiliently secured to said cradle, a bevelled friction drive member on the shaft of the motor, a cup-shaped friction driven member positioned around the cradle and provided at its brim with a bevelled friction surface, the friction member being resiliently urged in operative engagement with said surface, the driven member 10 being rotatably supported on and by the lower portion of said cradle, and a floor implement secured to said driven member.

11. In a machine of the class described, a U-shaped cradle, a motor positioned in the depression of the cradle, said motor having a base, one end of the base being pivotally mounted on one end of the cross-portion of the cradle on an axis parallel to the motor axis, the opposite end of the base being resiliently secured to the opposite end of the cross-portion of the cradle, a bevelled friction drive member on the shaft of the motor, a cup-shaped friction driven member positioned around the cradle and provided at its brim with a bevelled friction surface, the friction member 20 being resiliently urged in operative engagement with said surface, the driven member being rotatably supported on and by the lower portion of said cradle, and a floor implement secured to said driven member.
